SIDE FRAME

David M. Light, Chicago, Ill., assignor to American Steel Foundries, Chicago, Ill., a corporation of New Jersey

Application January 23, 1939, Serial No. 252,250

14 Claims. (Cl. 105—206)

My invention relates to side frames for railway car trucks and more particularly to such a form of frame generally designated truss type and comprising a tension member, a compression member and spaced columns integrally formed therewith.

In the conventional and other well known types of such side frames, the common practice is to provide an opening between the columns for insertion of the end of the associated bolster, said opening usually having a wider dimension at its lower portion to permit the insertion of said bolster end and, thereafter, the raising of said bolster end into the narrower portion of said opening and insertion of a spring group thereunder.

In a type of quick wheel change truck such as is described in my co-pending application bearing Serial No. 178,230, filed in the United States Patent Office December 6, 1937, it is possible to dispense with the widened portion at the bottom of the bolster opening between the columns and this makes it possible to avail of the space to strengthen the truss structure in a manner otherwise impossible.

The problem of strengthening the truss structure at the juncture of the columns with the tension member has commonly been complicated by the necessity for widening the tension member in the vicinity of the columns and between them to accommodate the spring grouping which supports the bolster end.

I have devised a novel form of truss structure for a truss type side frame which is particularly suitable for such types of quick wheel change trucks as described in my above mentioned pending application. My novel structure is of such form as to greatly strengthen the truss and at the same time enable the production of a frame of somewhat lighter weight than would otherwise be possible due principally to the manner of connection between said columns and the tension member of the frame.

An object of my invention is to devise a truss type side frame having a novel form of reinforcement at the juncture of each column with the tension member.

Another object of my invention is to devise a truss type side frame having columns whose web portions are angled adjacent their lower ends to join with the top chord of the tension member adjacent the middle portion of said tension member.

A different object of my invention is a novel form of truss side frame wherein the struts at

the opposite sides of the bolster opening are of generally triangular outline with the apices of said triangles defining the junctures of the compression member with said struts and the bases of said triangles defining the junctures of the tension member with said struts and wherein the extremities of the base of each triangle are widely spaced on opposite sides of the transverse vertical plane defined by the apex thereof.

A further object of my invention is to devise a novel form of side frame wherein a reinforcement is provided at the juncture of each column with the tension member in the form of a diagonal strut tapered to accommodate the usual spring grouping.

My invention further comprehends a novel form of integral column for a truss type side frame wherein the walls of said column are flared in both directions longitudinally of the frame to greatly increase the strength of the truss at the junctures of said columns with the tension member.

My invention also contemplates a modification of the above arrangement wherein the inner web of the column extends through the top chord of the tension member and is joined with the bottom chord thereof adjacent the transverse center line of the frame.

With these and various other objects in view my invention may consist of certain novel features more clearly set forth in the following description and the accompanying detailed drawings attached as well as in the accompanying claims.

Figure 1 is a top plan view of a side frame embodying my invention;

Figure 2 is a side elevation of the side frame shown in Figure 1, and Figure 3 is a bottom elevation thereof;

Figure 4 is a sectional view substantially in the vertical plane bisecting the truck transversely and as indicated by the line 4—4 of Figure 2;

Figure 5 is a sectional view in a horizontal plane taken substantially as indicated by the line 5—5 of Figure 2;

Figure 6 is a further sectional view in a horizontal plane adjacent the juncture of the column with the tension member substantially as indicated by the line 6—6 of Figure 2;

Figure 7 is a fragmentary side elevation corresponding in general to Figure 2, but showing a modified form of my invention; and

Figure 8 is a fragmentary sectional view corresponding in general to the view shown in Figure 4, but taken in the transverse vertical plane bi-

seeting the modified structure and substantially as indicated by the line 8—8 of Figure 7.

Describing my novel structure in greater detail, it may be noted that the side frame is of truss form having the compression member 2 and the tension member 4 merging adjacent their ends as at 6, 6 and having the integrally formed journal boxes 8, 8 of well known form, the juncture of the journal boxes with the ends of the tension member being reinforced by the parallel gussets 10, 10. Integrally formed with the tension and compression member are the spaced columns 12, 12 forming therebetween the bolster opening 14 and at either side thereof the window openings 16, 16. The top chord of the tension member between the columns is widened to form the spring seat 18 and said spring seat portion is reinforced by the ribs 20, 20 formed on the under side thereof, said ribs merging with the side walls 20 of the tension member as best seen in Figure 4. The bottom chord of the tension member is cored out beneath the columns as indicated at 22, 22 and said cored openings are beaded there-around as shown at 24, 24.

25 The upper portions of the columns have bolster guide surfaces 25, 25 of the form described in detail in my above mentioned co-pending application and of relatively great width (Figure 4), the configuration of which is best shown at 26, 30 26 (Figure 5), thus forming a window opening relatively narrow at the outboard side of the frame and relatively wide at the inboard side thereof, the said columns being formed with flaring guide surfaces therebetween. Along the 35 upper portions of the columns are the integrally formed brackets 28, 28 having at their upper ends the brake hanger jaws 30, 30 and supporting along their lower portions the vertical guide flanges 32, 32 forming, with the adjacent opposed side walls of the columns, vertical channels 34, 34 for the reception of guide lugs on the 40 associated bolster, all of said bracket structure being described in detail in my said co-pending application.

45 It will be noted that each of the columns 12 is of generally channel section from its upper end for about half the length thereof, having the middle web 36, the inner flange or side walls 38 and the outer flange or side wall 40. From 50 about the mid-point of the column as indicated at 42 the said inner and outer flanges or side walls of the column are gradually widened and shortly below the points 42 and as indicated at 44, 44 the center web of each column takes a 55 diagonal course toward the middle of the frame so that the juncture of the side walls with the tension member as indicated at 46 is a substantial distance longitudinally of the frame from the point 48 where the web of the column merges with the top chord of the tension member beneath the bolster opening near the transverse center line of the frame. Likewise from the point 44 the said center web 36 of the column is gradually narrowed, taking a tapered form 65 as best seen at 48 in the sectional view of Figure 4. This feature is further clarified in the sectional view of Figure 6 which is taken through said tapering portion and in the sectional view of Figure 5 which is taken above said 70 tapered portion and shows the manner in which said tapered portions merge with the spring seat as indicated at 52, 52 (Figure 5). Adjacent its lower end the side walls of each column are cored out to form the openings 58, 58 (Figure 2).

To those skilled in the art it will be apparent

that the widening of the bottoms of the columns to merge with the spring seat portion of the tension member as at adjacent points 48, 48 and to merge with diagonal portions of the tension member as at 46, 46 at points widely spaced longitudinally of the frame from the aforesaid points 48, 48 affords a truss structure of maximum strength able to support with less weight of metal than would otherwise be the case the present standard test requirements. The flaring 10 character of the bottoms of the columns enables me to form a novel truss structure, the essentially novel form of which is indicated by the triangular dotted outlines superposed upon Figure 2 and formed by the phantom lines A, 15 B and C.

The strength of the frame at the juncture of each column with the tension member is further increased by the manner in which the top chord 54 of the tension member extends between the 20 side walls of the columns as indicated at 56 (Figure 6) and the said upper chord of the tension member is further continued as indicated at 58, 58 (Figure 5) along opposite sides of the diagonal portions of the tension member, 25 ultimately to merge therewith as best seen at 60, 60 (Figure 3). The widened spring seat portion of the tension member is also continued upwardly along the diagonal portions thereof as best seen at 61, 61 (Figure 4).

In the modification shown in Figures 7 and 8 the structure is the same as that for the modification previously described except that the center web 36 of each column is carried diagonally through the top chord 54 of the tension member, 35 passing through the box section there-beneath as indicated at 64 to merge with the bottom chord of the tension member as at 66. The tapering form of the center web is continued in the portion that extends between the top 40 and bottom chords of the tension member as best seen in the sectional view of Figure 8.

In this modification it will be noted that the form of the triangular truss outline at A', B', C' differs from the previous modification in that 45 the lines A'—A' are somewhat longer than the corresponding lines A—A of the previous modification and the base line C'—C' merges therewith in the bottom chord of the tension member.

It is to be understood that I do not wish to 50 be limited by the exact embodiments of the device shown which are merely by way of illustration and not limitation as various and other forms of the device will, of course, be apparent to those skilled in the art without departing from the 55 spirit of the invention or the scope of the claims.

I claim:

1. In a side frame for a railway car truck, a compression member, a tension member and spaced columns forming therewith a bolster opening, brackets on the inboard faces of said columns forming therewith bolster guide channels, said tension member having a widened spring seat portion beneath said opening and diagonal end portions, each of said columns 65 having a generally triangular form with a web and inboard and outboard flanges, said flanges merging with said diagonal portions, and said web having for a major portion of its length a relatively great width as compared with the 70 width of said members and diverging inwardly from said portion of greater width to merge with said spring seat portion adjacent the transverse center line of said truck.
2. A truss side frame having a compression 75

member, a tension member, and vertical columns defining a bolster opening, said tension member having diagonal end portions and a horizontal mid portion and including a box section beneath said bolster opening, each of said columns having a general U section comprising a web and inboard and outboard flanges, brackets on said inboard flanges supporting vertical guide flanges centrally thereof to form with said columns 5 guide channels for an associated bolster, said webs having a relatively great width as compared with either of said members for a major portion of their length and forming inwardly flaring bolster guide surfaces, the lower portion 10 of each column flaring longitudinally of said frame so that the flanges thereof merge with the diagonal portions of said tension member and the webs thereof merge with the horizontal middle portion, said webs continuing through 15 the top cord of said box section to merge with the bottom chord thereof approximately at the transverse center line of said frame.

3. In a truss side frame, a tension member, a compression member, and spaced struts joining said members to form a bolster opening therebetween, said tension member having a box section beneath said bolster opening, each of said struts having a side elevation of generally 20 triangular form with the apex of said triangle at the juncture of said strut with said compression member, each of said struts having a U section comprising inboard and outboard flanges and a web forming a bolster guide surface of 25 relatively great width as compared with either of said members, said relatively great width extending from the top thereof for a major portion of the length of the strut, guide flanges on the inboard faces of said struts centrally thereof forming with the inboard flanges of said struts 30 guide channels for an associated bolster guide flange, said webs converging along the lower portions of said struts and continuing through the top chord of said tension member to merge with the bottom chord thereof approximately at the transverse center line of said frame.

4. In a truss side frame, a compression member, a tension member, and spaced struts forming a bolster opening, each of said struts having a generally triangular outline with the apex of said triangle defining the juncture of said strut with the compression member and the extremities of the base thereof defining the points of emergence of said strut with said tension member at areas widely spaced on opposite sides of the transverse vertical plane defining said apex, each of said struts presenting opposed inwardly flaring guide walls of relatively great width as compared with said members, said guide walls extending vertically downwardly uninterruptedly for a major part of their length, and brackets on said struts supporting centrally thereof vertical flanges forming with the flanges of said struts 45 guide channels for the guide flanges of an associated bolster.

5. A truss side frame having a compression member, a tension member, and spaced columns forming a bolster opening, said tension member comprising a horizontal beam of box section beneath said opening with top and bottom chords, each of said columns comprising inboard and outboard flanges and a transverse inwardly flaring center web forming a bolster guide surface of relatively great width as compared 50 with the width of said members, inboard brackets

6. A side frame having a tension member, a compression member, and vertical spaced columns with center webs and side walls, each of said side walls having a flaring bottom portion whose extremities merge with said tension member 5 substantial distances on opposite sides of the vertical plane defined by the vertical portion of said center web, one of said extremities being adjacent the transverse center plane of said frame, said center webs presenting, for a major portion of their length from the top downwardly, opposed inwardly flaring bolster guide faces of relatively great width as compared with the width of said members.

7. A side frame having a tension member, a compression member, and vertical spaced columns with center webs and side walls, each of said side walls having a flaring bottom portion whose extremities merge with said tension member 10 substantial distances on opposite sides of the vertical plane defined by the upright portion of said center web, one of said extremities being adjacent the transverse center plane of said frame, said center webs presenting, for a major portion of their length from the top downwardly, opposed inwardly flaring bolster guide faces of 15 relatively great width as compared with the width of said members, and brackets on the inboard faces of said columns forming opposed vertical guide channels centrally of said columns and inboard thereof for the reception of 20 guide flanges of an associated bolster.

8. In a truss side frame a compression member, a tension member having a widened spring seat portion of box section and diagonal end portions, integral columns having transverse webs and side flanges, the lower portions of said webs being diagonally arranged and tapered and continuing through the top chord of said box 25 section to merge with the lower chord thereof approximately at the transverse center plane of said frame and adjacent the vertical longitudinal plane bisecting said frame, the upper portions of said webs extending uninterruptedly vertically downwardly from the compression member to said lower portions, and brackets on the inboard faces of said columns forming therewith opposed vertical guide channels centrally of said columns and inboard thereof for cooperation 30 with the guide flanges of an associated bolster.

9. A side frame comprising a tension member with a horizontal spring seat portion of box section and diagonal ends, a compression member, and integral columns joining said members, each of said columns having diverging lower portions, one extremity of which extends through the top chord of said box section and merges with the lower chord thereof approximately at 35 the transverse center line of said frame and the other extremity whereof merges with the adjacent diagonal end, said extremities being spaced a substantial distance apart longitudinally of said frame on opposite sides of the vertical plane 40

defined by the guide surfaces of said columns, each of said columns having centrally thereof inboard of the bolster guide surface vertical flanges forming with said columns opposed vertical channels for cooperation with guide flanges on an associated bolster.

5. A truss side frame having a tension member, a compression member, and spaced columns, said tension member having a middle portion 10 with top and bottom chords, said columns having center webs, the top portions of which form bolster guide surfaces of relatively great width as compared with said members and the lower portions of which taper toward each other and 15 are continued through said top chord to merge with said bottom chord approximately in the transverse center line of said frame, and brackets formed on the inboard faces of said columns defining therewith opposed vertical channels centrally of said columns for cooperation with the guide flanges of an associated bolster.

11. In a truss side frame, a compression member, a tension member, and spaced columns forming therewith a bolster opening, said tension member having a box section beneath said opening, the juncture of each of said columns with said tension member being reinforced by diverging portions of said column merging with said tension member at widely spaced points on 25 opposite sides of the vertical plane defined by the guide portions of said columns, said guide portions having a relatively great width as compared with said members, and brackets centrally formed on the inboard faces of said columns defining therewith opposed vertical channels for cooperation with the guide flanges of an associated bolster.

12. In a truss side frame, a compression member, a tension member, and spaced columns 40 having bolster guide surfaces, the juncture of each of said columns with said tension member being reinforced by diverging portions merging with said tension member at widely spaced areas on opposite sides of the plane defined by said 45 bolster guide surfaces, one of said areas being adjacent the transverse center plane of said frame, and brackets formed on the inboard faces

of said columns centrally thereof and defining with said columns opposed vertical channels for cooperation with guide flanges of an associated bolster.

13. In a truss side frame having a tension member, a compression member and two columns merging therewith to form a bolster opening, said tension member having a box section below said opening with top and bottom chords, each of said columns having a generally triangular side elevation with side walls flaring adjacent their lower ends to merge with said tension member at widely spaced points, said columns presenting vertically arranged uninterrupted guide surfaces extending downwardly from the tops thereof for a major portion of their length and diagonally therefrom to their points of mergence with said top chord, each of said guide surfaces having a relatively great width as compared with the width of said members, and brackets on the inboard faces of said columns defining therewith opposed vertical channels for cooperation with the guide flanges of an associated bolster.

14. In a truss side frame having a tension member, a compression member and two columns merging therewith to form a bolster opening, said tension member having a box section below said opening with top and bottom chords, each of said columns having a generally triangular side elevation with side walls flaring adjacent their lower ends to merge with said tension member at widely spaced points, said columns presenting opposed webs of relatively great width as compared with the width of said members and forming vertically arranged uninterrupted guide surfaces extending downwardly from the tops thereof for a major portion of their length, said webs extending diagonally therefrom to their points of mergence with said top chord, and extending through said top chord to merge with said bottom chord adjacent each other, and brackets on said columns centrally thereof defining with said columns opposed vertical channels for cooperation with the guide flanges of an associated bolster.

DAVID M. LIGHT.
